UNITED STATES PATENT OFFICE.

HARRIE T. NOWOTNY, OF ST. LOUIS, MISSOURI.

CORD-FASTENER FOR WINDOW-SASHES.

1,178,595.

Specification of Letters Patent. Patented Apr. 11, 1916.

Application filed November 18, 1915. Serial No. 62,152.

To all whom it may concern:

Be it known that I, HARRIE T. NOWOTNY, a citizen of the United States, residing at St. Louis, State of Missouri, have invented 5 certain new and useful Improvements in Cord - Fasteners for Window - Sashes, of which the following is a full, clear, and exact description, reference being had to the accompanying drawings, forming a part 10 hereof.

My invention has relation to improvements in cord fasteners for window sashes; and it consists in the novel features of construction more fully set forth in the specification and pointed out in the claims.

The present invention is directed to improvements in weighted window-sashes, that is to say, sashes which are balanced by weights operating in boxes on the sides of 20 the window frame, the object of the invention being to so construct the sash as to allow the fastening of a new cable or chain to which the weight is secured, in case of 25 breakage of a worn out chain or cable, without the necessity of removing the sash from the window frame, and without disturbing the stop-head between which and the parting strip the sash operates.

A further object is to provide means for 30 fastening the end of the cable to the sash with a minimum expenditure of waste of cable.

A further object is to provide a special 35 cable securing member for the sash end of the cable applicable as well to old as to new sashes, all as will fully appear from the following detailed description of the invention in connection with the accompanying drawings, in which—

40 Figure 1 represents in inside elevation the lower left hand corner of a window frame and sash with my invention applied thereto, parts being broken away. Fig. 2 is an enlarged inner face elevation of one corner of 45 the lower sash with my invention applied, parts being broken away; Fig. 3 is an edge view of the sash looking toward the groove which receives the suspension cable, or a view looking toward the right at Fig. 2; 50 Fig. 4 is a horizontal cross-section on the line 4—4 of Fig. 2; Fig. 5 is a plan of the disk or plate covering the cable-loop at the base of the depression or basin formed for its reception in the sash-frame; and Fig. 6 55 is a plan of the star-disk with a portion of the arms turned at right angles to the

disk showing the manner of forming the prongs which engage the cable coil or loop behind the cover plate shown in Fig. 5.

Referring to the drawings, F represents 60 the window frame, S the lower sash, c, c', the suspension cords or cables for the lower and upper sashes, W' the balance weight for the upper sash, B the weight-box, a, the inner stop-head, all as fully understood in 65 the art.

My present improvement being applied to both sashes, a description of the invention in connection with one side of the lower sash will be sufficient for our purpose.

As previously stated, one of the objects sought is to secure the cable to both the sash S and weight W, with a minimum length of cable. In the present embodiment of my invention the weight-carrying end of 70 the cable is fastened to the weight by any suitable means. The opposite or outer end of the cable is passed through the groove m, through the passage n, into the chamber or pocket P formed in the side member of the 75 sash, a single loop L being formed in the cable, after which the free end is inserted into the socket p leading from the pocket. In the present embodiment of my invention 80 I employ a pronged star-shaped or equivalent serrated disk 3 provided with radial arms t which are bent at right angles to the disk to form prongs or teeth, these prongs being embedded or forced into the coil L after which a circular cover plate or disk 4 85 is placed over the pronged disk 3, said cover plate being received by the annular seat d disposed about the entrance to the pocket P and depressed below the face of the sash frame, said plate when in place, coming flush with the outer face of the sash. After that a securing screw s is passed 90 through the registering openings o o' of the respective disks, and through the opening of the coil L, thus anchoring the outer end 95 of the cable to the sash. In the event the cable c breaks, and it becomes necessary to replace the broken cable with a fresh cable, the operator first detaches the cable from the weight in the weight-box. He then un-screws the screw s and removes the disks 3 and 4, and pulls out the other portion of the 100 broken cable from the front of the sash. To attach a fresh cable, the operator first drops a "mouse" through the top of the groove m, drawing the lower end of the mouse through the passage n and pocket P and to this end

ties the new cable. He then pulls the mouse up thereby drawing the cable after it through the pocket *P*, passage *n* and groove *m*, the lower end of the cable being shoved 5 into the socket *p*, and by slightly relaxing the tension on the cable, the loop *L* will form almost automatically within the pocket *P* (or the operator may form such loop in the event the cable is too stiff to coil automatically), after which the pronged disk 10 *3* and cover disk *4* are applied, the screw *s* reinserted and driven through the opening of the loop and firmly screwed in place, thereby anchoring the outer end of the new 15 cable to the sash. The mouse with the cable still attached is then passed over the pulley *w* into the weight box *B* drawing the cable after it, after which the inner end of the cable is attached to the weight in the box.

20 Having described my invention what I claim is:—

- 25 1. A window sash provided with a side groove for the reception of a suspension cord and with a pocket communicating with said groove for receiving one end of the cord, said pocket opening through the front face of the side of the sash, a cover plate secured to the sash, for closing the pocket, and a serrated member in the rear of the cover plate for engaging the end of the cord in the pocket.
- 30 2. A window sash provided with a side groove for the reception of a suspension cable, and with a pocket communicating

with said groove for receiving one end of the cable, a depression in the face of the sash at the outer terminal of the pocket, a serrated disk for engaging the cable in the pocket, and an outer cover plate deposited in the depression and jointly with the serrated disk secured to the sash, whereby the cable is securely anchored to the sash.

3. A sliding window sash provided with a side suspension cable, a pocket formed on the side of the sash opposite the face of the sash, said pocket opening outwardly through the face of the sash, a groove formed in the sash for receiving the cable, a passage establishing communication between the groove and pocket, a socket leading downward from the pocket for receiving the lower terminal of the cable, the latter being adapted to be looped in the pocket, a circular depression bounding the outer end of the pocket for receiving a cover plate for the pocket, a pronged disk interposed between the cable loop and cover plate, the prongs thereof engaging the said loop, and a screw traversing the plates and loop and screwed to the sash, whereby the outer end of the cable is anchored to the sash.

In testimony whereof I affix my signature, in the presence of two witnesses.

HARRIE T. NOWOTNY.
